DESIGN FOR A PICNIC FORK

Charles Lee Osborn, Cheyenne, Wyo.

Application June 3, 1944, Serial No. 113,854

Term of patent 7 years

(Cl. D54—12)

To all whom it may concern:

Be it known that I, Charles Lee Osborn, a citizen of the United States, residing at Cheyenne, in the county of Laramie and State of Wyoming, have invented a new, original, and ornamental Design for Picnic Forks, of which the following is a specification, reference being had to the accompanying drawing, forming part thereof.

In the drawing:

Fig. 1 is the top view of a picnic fork showing my new design; and

Fig. 2 is a side view thereof.

I claim:

The ornamental design for a picnic fork, as shown and described.

CHARLES LEE OSBORN.
